UNITED STATES PATENT OFFICE.

JOHN C. HATZEL AND EDGAR L. MORLEY, OF NEW YORK, N. Y.

ELECTRICAL RECEPTACLE AND PLUG.

No. 823,724.

Specification of Letters Patent.

Patented June 19, 1906.

Application filed February 2, 1904. Serial No. 191,734.

To all whom it may concern:

Be it known that we, JOHN C. HATZEL and EDGAR L. MORLEY, citizens of the United States, residing at New York, in the county 5 and State of New York, have invented certain new and useful Improvements in Electrical Receptacles and Plugs; and we do hereby declare the following to be a full, clear, and exact description of the invention, such 10 as will enable others skilled in the art to which it appertains to make and use the same.

The invention relates to improvements in plug-receptacles for electric circuits; and it 15 consists in the novel features and combinations hereinafter described, and particularly pointed out in the claims.

The object of the invention is to produce a receptacle the arrangement of which is such 20 that no splicing to circuit-wires is necessary where the receptacle is not connected to the end of a circuit, the four binding-posts being provided so that the circuit-wires can be cut and attached to the receptacle proper, avoiding 25 the necessity of a tap, with the possibility of a tap being poorly insulated by careless workmen, which is particularly the case in iron outlet-boxes, where the taps are apt to be jammed back into the iron box.

Furthermore, the object is to produce a 30 plug with which it is an absolute impossibility to short-circuit the receptacle when inserting the plug, as is the case with a great many receptacles and plugs now on the market and where in an iron conduit system the face-plates of such receptacles are necessarily 35 in metallic connection with the iron box and iron conduit system. With this plug and receptacle it is impossible to make contact with 40 the plate and one of the contacts of the terminals and the receptacle at the same time, thereby creating a possibility of a short circuit.

Finally, the object of this invention is to 45 provide an improved device of this class which will be relatively simple and inexpensive in construction, convenient in installation, unobstructive, and neat in appearance and generally superior in point of efficiency 50 and adaptable to varying conditions of use.

In the drawings, Figure 1 represents a longitudinal vertical section of our improved receptacle with the plug in position. Fig. 2 represents a plan view of the same. Fig. 3 55 represents a vertical cross-section taken on

lines x x in Fig. 2. Fig. 4 represents an exterior end view of the receptacle with the plug in position. Figs. 5 and 6 represent, respectively, a side and end view of our improved plug; and Fig. 7 represents a plan view of the under side of our improved plug.

a designates a receptacle, of porcelain or other non-conducting material; b , the plug, removably located within said receptacle, and c , in dotted lines, the outer face-plate 65 adapted to be secured to said receptacle and also to the wall, floor, or other support to which the receptacle may be applied.

The receptacle a is preferably rectangular in outline, as shown in the drawings, and provided with the recessed end extension a' . Secured within the receptacle a upon the shoulders a' by means of the countersunk screws a' a' are the L-shaped contact-springs d d' and the contact-plates e and e' . The contact-plates e and e' are each provided with two binding-screws f and f' , which receive the ends of the main wires and are in electrical connection with the contact-springs d and d' . The plates e and e' are provided with the inward projections e^2 for the purpose of limiting the inward thrust of the plug b , as herein-after described. The contact-springs d and d' are in the form of L-shaped plates extending from beneath the contact-plates e and e' 80 downward and outward along the inner wall of the receptacle a to bear upon the corresponding contact-springs connected to the plug b .

The receptacle a has at its upper opposite ends projections h^2 h^2 , which projections are provided near each corner with an open slot (lettered g , g' , g^2 , and g^3) through which the main conducting or insulated leading-in wires may be passed to the binding-screws f 95 and f' . The inner part of the receptacle is entirely open adjacent to and coincident with the openings g , g' , g^2 , and g^3 , and hence every possible facility is afforded for making desirable wire connections. h and h' are metallic plates or lugs set in recesses formed in the lugs h^2 on the top of the non-conducting receptacle a and held in position by means of screws i and i' . The outer face-plate c is secured to said metallic plates in any well-known manner.

The receptacle a is so constructed that it can be installed in any of the standard switch outlet-boxes in use on the market either by securing the metallic plates h h' to 110

the lugs on the said boxes or by reversing the screws i i' and screwing the same into the lugs within the said boxes.

The plug b is made of porcelain or other suitable non-conducting material and is of rectangular outline, adapted to closely fit within the mouth of the receptacle a . The outer end or face of the plug b has a central tubular projection j , which is provided with a central orifice k . The orifice k terminates in a central cavity or bowl-shaped recess l a short distance below the tubular projection. Two sides of the plug b are recessed for the reception of the outwardly and upwardly flaring contact-springs m and m' , which, together with the contact-plates n and n' , are held in position by means of the countersunk screws o and o' . The contact-plates n and n' are each provided with a binding-screw, (lettered p and p' .)

The insulated conducting-wires are passed through the central orifice k , and both pieces are knotted together, and the ends of the conducting-wires are clamped under the heads 25 of the binding-screws p and p' , after which the two wires are pulled through the central orifice k until the knot is firmly seated in the bowl-shaped recess or cavity l , thereby serving as a stop to prevent the breaking of the 30 connections with the binding-screws, which might otherwise occur should an accidental strain be exerted on said wires. q and q' are recesses formed in the opposite sides of the plug b to form convenient gripping-surfaces 35 for the fingers during the insertion of the plug into and its withdrawal from the receptacle a .

The recesses in the two sides of the plug b for the reception of the contact-springs m and m' and the recess in the bottom are formed by the projecting flanges r , r' , and r'' , designed to engage with the inner walls of the receptacle a , the object of these projecting flanges being to extend beyond the contact-springs m and m' and prevent any possibility 45 of short-circuiting during the insertion of the plug into or its withdrawal from the receptacle a . The flange r'' also serves to limit the inward thrust of the plug b by contacting 50 with the projection e^2 of the plates e e' .

It will be noted that by our construction provision is made for a large area of contact between the contact-springs d and m and d' and m' , respectively, and inasmuch as the 55 springs d and d' form a tapered space within the box and the springs m and m' form a structure of wedge or tapered shape it will be obvious that perfect contact of large area is obtained, and when withdrawing the plug 60 from the receptacle a quick break is had, whereby danger of arcing is obviated.

By the structure above described it will be obvious that tap-wires are unnecessary, as the main conducting-wires may be cut adjacent 65 to the receptacle and the four ends of said

wires secured to the four binding posts or screws f f' , respectively. However, we do not wish to be understood as implying that tap-wires cannot be used in connection with our device, for it is clear that a tap-wire could be led from each of the main wires to the binding-screws f f' through the slots g g^2 , whereby a complete and operative circuit could be closed by means of the above-described plug. 70

It will be understood that the special construction and arrangements and combinations of parts herein shown are given only to illustrate one practical embodiment of the invention, and hence we do not wish to be understood as limiting ourselves to the exact details of construction herein shown, as the same may be varied in practice without departing from the scope of our invention. 75

Having thus described our invention, what 85 we desire to secure by Letters Patent of the United States is—

1. An electrical receptacle having a recessed extension at each end adjacent to its open side, each extension provided with slots, 90 a contact-spring secured in each recess, the free end of each spring projecting into the interior of the receptacle, means in connection with each contact-spring for securing a circuit-wire directly thereto, whereby the use of 95 intervening tap-wires is avoided.

2. An electrical receptacle comprising an oblong box made of insulating material, open on its upper side, extensions provided with recesses and open slots located at the ends of 100 the open side of said box, L-shaped contact-springs secured in said recesses and projecting inwardly into the body of the box, contact-plates resting upon said springs means for securing said plates and springs within 105 said recesses, means for securing the ends of circuit-wires to said plates, a plug for said receptacle, said plug having oppositely-disposed pole-pieces for contact with the L-shaped springs of said receptacle. 110

3. An electrical receptacle, comprising an oblong porcelain box open upon its upper side, recessed extensions provided with open slots on the upper side of said box, contact plates and springs secured in said recessed extensions, said springs extending into said box, means for securing circuit-wires to said contact-plates, and a plug for said receptacle, said plug having contact-springs secured upon its opposite sides for contact with the 120 contact-springs of said receptacle. 115

4. An electrical receptacle comprising an oblong porcelain box open upon its upper side, recessed extensions located at the ends of the open side of said box, two open slots 125 leading from the outer side of each of said recessed extensions, means for securing circuit-wires in said recessed extensions, and a plug having leading-out wires and contact-springs for insertion into the open side of said box. 130

5. An electrical receptacle consisting of an oblong hollow box, provided with recessed extensions on the opposite ends of its open side, two open slots in each of the said recessed extensions, and means for securing electrical connections in said recessed extensions, such connections leading out through said open slots.

6. An electrical receptacle comprising an oblong box made of insulating material, open on its upper side, extensions provided with recesses and open slots located at the ends of the open side of said box, L-shaped contact-springs secured in said recesses and projecting inwardly into the body of the box, contact-plates resting upon said springs, means for securing said plates and springs within said recesses, and means for securing the ends of circuit-wires to said plates.

7. An electrical receptacle comprising an oblong porcelain box open upon its upper

side, recessed extensions located at the ends of the open side of said box, two open slots leading from the outer side of each of said recessed extensions, means for securing circuit-wires in said recessed extensions.

8. An electrical receptacle, comprising an oblong porcelain box open upon its upper side, recessed extensions provided with open slots on the upper side of said box, contact plates and springs secured in said recessed extensions, said springs extending into said box, means for securing circuit-wires to said contact-plates.

This specification signed and witnessed this 25th day of January, 1904.
